JOURNAL BOX AND METHOD OF MAKING
THE SAMEFrank C. Hasse, La Grange, Ill., assignor, by means
of assignments, to Union Carbide and Carbon Cor-
poration, a corporation of New York

Application April 12, 1935, Serial No. 15,942

2 Claims. (Cl. 29—166)

This invention relates to a journal box, and more particularly a journal box which is flame-cut from a single forged or rolled billet. The invention also relates to a method of making the journal box. The invention is especially useful in connection with the construction of improved locomotive driving boxes, but it is equally applicable to other types of journal boxes.

In the past it has been customary to form journal boxes by first casting the part and then machining certain surfaces thereon. The resulting journal box has accordingly been subject to the limitations of castings; the reliability of its performance has been uncertain, and its life has generally been short. This is particularly true of locomotive driving boxes, which must sustain horizontal thrust as well as vertical dead weight.

One object of the invention therefore, is to provide a journal box which will have the properties of a forged or rolled member. Another object is the provision of such a journal box in economical form, and so shaped as to require the minimum amount of machining. A further object is to provide an inexpensive process of cutting such a part from a rolled or forged billet. Other objects will become apparent from the present specification.

The invention is shown by way of illustration, in its application to a locomotive driving box, in the accompanying drawing, in which:

Fig. 1 is a plan view of a driving box constructed in accordance with the invention;

Fig. 2 is a view taken on the line II—II of Fig. 1, being half vertical elevation, half mid-section; and

Fig. 3 is an elevation of the driving box as seen from the right in Fig. 1.

I have found that a serviceable journal box may be produced by cutting a single solid steel billet of substantially rectangular cross section to the desired contour by means of an oxygen jet and a gas flame such as an oxy-acetylene preheating flame. I have found further that such flame-cutting may be expeditiously performed if applied to a hot billet either as it comes from the rolls or after being re-heated.

Referring now more particularly to the drawing, they show outlined in broken lines 10 and 11 a billet from which a locomotive driving box 12 is cut, the billet having dimensions greater than but approximately the outside dimensions of the box. The driving box 12 is made in the usual form with a recess extending inwardly from the bottom surface of the box and prominences 13 interiorly thereof forming ledges 14 on

opposite walls of the recess at the ends of an arcuate socket 15 for the support of the usual crown brass (not shown). The driving box extends beneath the prominences 13 on either side to provide space for the accommodation of the usual lubricating cellar (not illustrated).

The contour of the driving box is cut from the solid billet by guiding a cutting oxygen jet over the billet which is heated along the line of cut to the ignition temperature of steel in oxygen, 10 as by an accompanying oxy-acetylene preheating flame. Preferably the billet is first stood with the face shown in Fig. 1 upward, and the contour of the faces of the billets are flame-cut to the pattern of the ends of the box, including 15 the recesses 16 and the adjacent shoulders 17 and 18. Following this, the billet is laid on its side with the side face illustrated in Fig. 2 upward, and the interior contour shown in Fig. 2 is cut into the billet from its bottom surface to remove 20 metal and leave a recess, including the outline of the arcuate socket 15, the ledges 14, and the prominences 13. While still in this position the exterior outline 19 at the foot or bottom of the driving box is cut, followed by the contour 20 at 25 the top of the driving box. The billet is now shifted to stand on end with the end face illustrated in Fig. 3 upward, and the contours 21 and 22 at the top and bottom of the billet are then cut. 30

The contours 20, 21 and 22 at the opposite faces constituting the top and bottom surfaces of the driving box may be cut to finished dimensions. All other cuts, however, should be made to allow stock for subsequent machining. 35

Thus, the faces of the prominences 13, the ledges 14, the arcuate socket 15, and the recesses 16 together with the shoulders 17 and 18 comprising the end contour surfaces of the driving box, are cut to allow for machining and are subsequently machined. During the machining operations following the flame-cutting of the driving box from the billet, spring saddle seats 23 may be milled, or drilled and chipped out of the top of the driving box. Also, during machining operations, the hub side of the driving box may be machined out at 24 to a slight depth, say $\frac{1}{4}$ inch, to permit accommodation of the usual thrust bearing bronze. 45

Oil cavities 25 may be subsequently drilled in 50 the driving box, and also ducts 26 connecting the oil cavities with the innermost face of the adjacent recess 16.

Clearly, the driving box may be cut directly from the billet as it comes from the rolls, utilizing 55

the original heat given thereto. Usually, however, it will be necessary to reheat a cold billet before flame-cutting the driving box. Preferably the temperature of the billet being cut should be at least 750° Fahrenheit, and if desirable between this lower limit and 850° Fahrenheit as an upper limit. However, it is possible to flame-cut a driving box directly from a cold billet, although such an operation requires considerably greater gas consumption. The cutting instrument is preferably a gas cutting machine, for instance, using appropriate patterns or templets and such a machine as that disclosed in Patent No. 1,774,865 for "Blowpipe apparatus," granted September 2, 1930, to Isaiah Allison; but a hand-operated blowpipe may be used.

It will be appreciated that a unitary driving box cut directly from a forged or rolled steel billet has the strength and lasting qualities of the steel or iron forging of which it is made, and breakage of such driving boxes, when properly designed, is substantially impossible under normal service conditions. Furthermore, the expense necessitated by replacing broken driving boxes is eliminated. Finally, the metal from which such driving boxes are cut is especially adapted to welding and to being built up by the oxy-acetylene method, as a result of which the service life of such a part may be extended almost indefinitely by welding additional metal to the part as it becomes worn.

From the foregoing it will become apparent that the necessity of maintaining in locomotive shops extensive stocks of castings for the various types of driving boxes is eliminated when the boxes are formed as described. It is merely necessary to keep on hand a few billets of proper general dimensions from which the driving boxes may be cut without delay according to the pattern desired.

While the particular description given herein refers to driving boxes it will be apparent that the same principles and the same method may be

applied in forming other journal boxes with substantially the same advantages. Thus, the same method may be applied to form engine truck journal boxes, trailer truck journal boxes, or similar journal boxes for electric locomotives, oil locomotives or gas-electric motors. Any or all of these may be flame-cut to the desired pattern by the same general procedure. The foregoing description is therefore, to be taken merely as one example of how the invention may be applied. 10

I claim:

1. A unitary steel journal box made from a solid steel billet of substantially rectangular cross section, said journal box having contour portions at opposite faces thereof flame-cut to finished dimensions and constituting the top and bottom surfaces of said box; the contours of the end and side faces of said box comprising machined flame-cut surfaces; and a recess extending inwardly from said bottom surface and having ledges on opposite walls thereof and a crown brass receiving socket at its inner end, at least said socket and said ledges within said recess having machined flame-cut surfaces. 15

2. A method of making a unitary steel journal box which comprises providing a solid steel billet of substantially rectangular cross section and having dimensions which are greater than but approximately the outside dimensions of said box; flame cutting contour portions of two opposite faces of said billet to finished dimensions to form the top and bottom surfaces of said box; flame cutting contours of the end and side faces of said billet to the patterns of the ends and sides of the box but allowing sufficient metal for machining; 35 flame cutting into said billet from said bottom surface to remove metal and leave a recess having ledges on opposite walls thereof and a crown brass receiving socket at its inner end; and machining said socket, said ledges, and portions of such flame-cut ends and sides. 40

FRANK C. HASSE.
